UNITED STATES PATENT OFFICE.

EDMUND MORRIS, OF MICHIGAN CITY, INDIANA.

DESIGN FOR CANE FABRIC.

SPECIFICATION forming part of Design No. 26,857, dated March 30, 1897.

Application filed February 18, 1897. Serial No. 624,050. Term of patent 3½ years.

To all whom it may concern:

Be it known that I, EDMUND MORRIS, a citizen of the United States, residing in Michigan City, in the county of La Porte and State of Indiana, have invented and produced a new and original Design for Cane Fabric, of which the following is a specification, and which is illustrated in the accompanying drawing, showing a face view of a small piece of fabric with my design applied.

Cane fabric containing my design has alternate close-woven and open-mesh stripes A and B, to the former of which is applied a chain-shaped figure. Each stripe A is made up of a series of parallel strips a , arranged close together and divided up into short lengths or sections a' by a series of cross-strips a'' , and each stripe has applied to it a chain-shaped figure x , running parallel with the strips a . Each stripe B has a series of

pairs of strips b , which form continuations of the cross-strips a'' and which, with the strips running at right angles to them and the diagonal strips b' , form a series of polygonal figures x' . Each alternate diagonal strip b' ²⁵ is colored or striped, as shown.

The leading feature of my design is the alternately-arranged close-woven and open-mesh stripes, the former of which each contains a chain-shaped figure. ³⁰

I claim—

The design for cane fabric substantially as herein shown and described.

In testimony whereof I have hereunto subscribed my name.

EDMUND MORRIS.
